(57) **CLAIM**

The ornamental design for a scoop utensil for gathering beads, as shown.

DESCRIPTION

FIG. 1 is a perspective, front view in elevation of a scoop utensil for gathering beads;

FIG. 2 is a perspective, rear view in elevation of the scoop utensil for gathering beads of FIG. 1;

FIG. 3 is a front view in elevation of the scoop utensil for gathering beads sewing thimble of FIG. 1;

FIG. 4 is a rear view in elevation of the scoop utensil for gathering beads of FIG. 1;

FIG. 5 is a right side view in elevation of the scoop utensil for gathering beads of FIG. 1;

FIG. 6 is a left side view in elevation of the scoop utensil for gathering beads of FIG. 1;

FIG. 7 is a top plan view of the scoop utensil for gathering beads of FIG. 1; and,

FIG. 8 is a bottom plan view of the scoop utensil for gathering beads of FIG. 1.

The broken lines on FIGS. 2 and 4 indicate an area for labelling, but form no part of the claimed design.
